SHUTTLE-BOX TENSION-CONTROLLING MECHANISM FOR LOOMS.

Application filed March 9, 1925. Serial No. 13,948.

The present invention relates to an improvement in shuttle box tension controlling mechanism for looms.

The object of the invention is to reorganize shuttle box tension controlling mechanism for looms in order to secure an improved operation of the shuttle, and the invention consists in the mechanism herein-after described and particularly defined in 10 the claims.

In the accompanying drawings illustrating the preferred form of the invention, Fig. 1 is an end elevation of a part of a loom showing the lay in section; Fig. 2 is a front view of the lay, one of the swords and associated parts; and Fig. 3 is a section taken on the line 3—3, Fig. 1.

The illustrated embodiment is described as follows: A portion 10 of the loom frame 20 is shown in end elevation supporting the frog 11. As shown in Fig. 1, the front of the loom is at the left of the drawing, and the back of the loom is at the right of the drawing. The lay 12 supported by the 25 swords 13 carries the shuttle box indicated in a general way by the reference character 14, the binder 15 being shown in dotted lines. The dagger shaft 16 is mounted in brackets below the lay beam, and its end 30 17, bent at right angles to the body of the shaft, carries the binder finger 18 which in turn carries the binder finger adjusting screw 19 which takes against the binder.

Integral with the dagger shaft 16 is the 35 dagger 20 adapted to engage the steel 21 of the frog 11. Mounted on the dagger shaft is a bell crank lever 22 which has a downwardly extended arm 23 and a forwardly extended arm 24. This bell crank 40 lever 22 is secured to the dagger shaft by means of three set screws 25. A second bell crank lever 26 is pivotally mounted upon the stud 27, which is carried by the bracket 28 clamped to the sword 13 by means 45 of the clamp piece 29 and bolt 30. The upwardly extended arm 31 of the bell crank lever 26 is provided with a flat face 32 which engages the finger 33 projected at right angles from the end of the arm 23 in front 50 of the face 32 of the arm 31, see Fig. 2. The horizontal arm 34 of the bell crank

lever 26 is connected at its end with the end of the horizontal arm 24 of the bell crank lever 22 as follows:—The rod 35 has a right angle portion 36 at its upper end which is received in a hole in the end of the arm 24. The lower end of the rod 35 passes through the two ears 37 and 38 of the yoke 39, which latter is provided with a pin 40 received in a hole in the end of the arm 34 of the bell crank lever 26. The rod 35 is screw-threaded on its end, and screwed upon it is a dagger stop 41 which is held in adjusted position by a set nut 42. This dagger stop is provided with a sleeve 43 integral therewith, which embraces the rod 35 and fits within a hole in the ear 38. On the rod 35 above the ear 38 is the dagger spring adjusting nut 44, adapted to be secured in adjusted position by the lock nut 45. The 70 nut 44 is provided with a sleeve 46 which forms a spring seat for the dagger spring 47, which encircles the rod and takes against the adjusting nut 44 at one end, and against the ear 37 at the other end. 75

The rod 35 attached to the arm 24 operates as a connection to the dagger to prevent overthrow thereof by a yielding engagement with the yoke 39 through the medium of the spring 47 and by the positive stop when 80 the nut 41 strikes the ear 38 of the yoke 39 so that upward movement of the arm 24 and therefore overthrow of the dagger is positively prevented.

The operation of this mechanism is as 85 follows: When the shuttle box is empty the spring 47 exerts its pull upon the rod 35 to thereby turn and hold the dagger 20 depressed. As shown in Fig. 1, the parts 90 occupy the positions which they assume when the shuttle is standing in the box, but when the box is empty the dagger is pressed downwardly by the spring and occupies a position such that it will engage the steel 21 of the frog 11. When the shuttle is about to enter 95 a box it will be understood that the binder 15 is somewhat to the left of the position shown in Fig. 1, being pressed into such position by the dagger finger 18, and that the dagger shaft 16 is turned owing to this 100 shuttle absence, so that the dagger 20 is lowered. Now the shuttle strikes the binder

and throws it violently out. This presses back the dagger finger, lifts the dagger and exerts an upward pull on the rod 35, tending to compress the dagger spring 47. At 5 the same time the downwardly extending arm 23, by reason of the movement of the dagger shaft, moves the vertical arm 31 of the bell crank lever 26 so as to cause its arm 34 to pull downwardly upon the yoke 39, 10 so that not only is the spring resistance to outward movement of the dagger fingers equal to the compression of the spring by the pull upon the rod 35, but in addition by the pressure super-added thereto of the 15 downward movement of the yoke 39. The blow which the shuttle delivers to the binder being transmitted violently to the dagger finger causes a rapid motion to be imparted to the downwardly extended arm 23 of the 20 bell crank lever 22, and it not only moves the bell crank lever 26, but causes it to overthrow, that is to say, it begins to move it while the arms 23 and 31 are in contact, and then after the arm 23 comes to rest, the arm 25 31 continues its movement due to its momentum. This results in moving the yoke 39 downwardly until the ear 38 comes into contact with the dagger stop 41 and the bell crank lever 31 and yoke 39 deliver a 30 blow to the dagger stop which is transmitted through the rod 35 to the dagger shaft and binder fingers.

The outward movement of the dagger fingers, therefore, under the blow of the 35 entering shuttle, is first resisted by a yielding opposition exerted by the spring 47, and finally terminated by the positive engagement of the yoke with the dagger stop nut 41, which delivers a counter-blow to the 40 dagger finger, tending to move it in a direction to cause it to exert pressure on the binder.

This mechanism, therefore, contemplates 45 a means for applying pressure to the binders by which the first blow of the binders against the binder finger is caused to deliver a counter-blow upon the binder finger, tending to turn the latter to engage with the binder owing to the momentum of a part set 50 in motion by the first blow.

The condition of adjustment of the parts is such that the pressure of the binder on the shuttle is small at the time of the pick, being the light pressure of the dagger spring 47. When the box is empty the binder extends the usual distance into the box, but when the shuttle strikes the binder, the binder is prevented from moving outwardly 55 as far as in ordinary constructions of shuttle box binder operating mechanism; that is to say, while the binder is adjusted it will extend just as far into the box as is ordinarily the practice, such binder does not move outwardly much beyond the position to which 60 it is necessarily moved in order to permit

the shuttle to enter the box, as a result of which the outward overthrow of the binder is not great, and it is promptly returned to press upon the shuttle and resist its entrance by the momentum of a part set in motion by 70 the outward movement of the binder, so as thereby to cause further and greater pressure on the shuttle as it continues its movement in entering the box.

This shuttle box tension mechanism is 75 little affected by temperature variations, or by variations of humidity, or by the accidental occurrence of oil or moisture on the shuttle. Without this mechanism such conditions sometimes cause shuttles to rebound, 80 but with the present construction a much more continuous pressure is applied to the shuttle as it enters the box, with the result that the rebound is greatly lessened.

One of the features of the operation of 85 this mechanism which is of advantage resides in the fact that because the throw of the binders is reduced, the shuttle is brought to rest more as a result of the continuous application of friction to the shuttle than as 90 a result of the nice balancing of a blow against the part to be moved thereby. That is to say, instead of stopping the shuttle by causing it to strike the binder a severe blow, after which the binder is moved so far that 95 for a certain part of the entering movement of the shuttle it is not in contact with the shuttle at all, the shuttle strikes the binder with a much less severe blow, and the binder is out of contract with the shuttle a very 100 much shorter length of time, whereupon contact is resumed, with the result that the friction applied to the shuttle by the binder is distributed over a longer period of time. This results in a lessened heating of the 105 shuttle, and consequently a lessened wear of the shuttle, and in more uniform operating condition.

The exact mode of operation and the 110 reasons for the satisfactory results accomplished are not precisely known nor understood, but the foregoing explanation is that which the applicant believes to be correct.

The bell crank lever 26 is shown as provided with a rearwardly extended arm 48, 115 having an enlargement or weight 49 at its rear end. This may be used if desired, but the description of the operation of the mechanism is the same irrespective of whether this weight be used or not. 120

Having thus described the invention, what is claimed is:

1. Shuttle box tension controlling mechanism for looms having, in combination, a lay, swords upon which the lay is mounted, 125 shuttle boxes for the lay, binders for the shuttle boxes, pressure applying means for the binders comprising a bell crank lever having a long arm and a short arm pivoted on the sword below the lay, the long arm 130

parallel to the sword, and the short arm extended substantially at right angles thereto, and yielding connections between the pressure applying means and the binders.

5 2. Shuttle box tension controlling mechanism for looms having, in combination, a lay, swords for the lay, shuttle boxes on the lay, binders for the shuttle boxes, a dagger shaft mounted on the lay, dagger

10 fingers carried thereby operating to cause pressure to be exerted upon the binders, a bell crank lever secured to the dagger shaft having an arm extended downwardly parallel to the sword, and a second arm ex-

15 tended at substantially right angles thereto, a second bell crank lever mounted on the sword having a long arm extended upwardly parallel to the lay and having a face engaging the downwardly extended

20 arm of the bell crank lever on the dagger shaft, said second bell crank lever having an arm extended at right angles to the first arm, and yielding connections between the horizontal arms of the two bell crank levers.

25 3. Shuttle box tension controlling mechanism for looms having, in combination, a lay, shuttle boxes on the lay, binders in the shuttle boxes, a dagger shaft mounted on the lay provided with daggers and binder

30 fingers, said dagger shaft being provided with horizontal and vertical arms, a bell crank lever pivotally mounted on the lay having horizontal and vertical arms, the vertical arms of the two levers engaging

35 each other, and the horizontal arms of the two levers being yieldingly connected by a rod and spring contrivance operating as a yielding dagger stop to vary the binder tension so as to increase it suddenly at the

40 beginning of the back stroke of the lay.

4. Shuttle box tension controlling mechanism for looms having, in combination, a lay, shuttle boxes for the lay, binders for the shuttle boxes, pressure applying means

45 for the binders comprising a part which receives the blow of the binder and causes a second part to be set in motion thereby, which second part, due to the momentum derived from such blow, delivers a counter-

50 blow to the first part, tending to return it to cause it to apply pressure to the binder.

5. Shuttle box tension controlling mechanism for looms having, in combination, a lay, shuttle boxes for the lay, binders for the shuttle boxes, a dagger, a dagger rod, 55 a dagger spring, a dagger stop, and a part connected with the binders and the dagger stop actuated by the opening of the binders to be thrown against the dagger stop to cause pressure on the shuttle through the 60 binders.

6. Shuttle box tension controlling mechanism for looms having, in combination, a lay, shuttle boxes for the lay, binders for the shuttle boxes, a dagger, a dagger rod, 65 a dagger spring, a dagger stop, and connecting mechanism acting automatically on the entrance of a shuttle into a box to impart momentum to such mechanism to cause pressure to be exerted upon the binders. 70

7. Shuttle box tension controlling mechanism for looms having, in combination, a lay, shuttle boxes for the lay, binders for the shuttle boxes, a dagger, a dagger rod, 75 a dagger spring, a dagger stop, and connections set in motion by the shuttle entering the box to cause the momentum of the connections to again bring pressure upon the binders.

8. Shuttle box tension controlling mechanism for looms having, in combination, a lay, shuttle boxes for the lay, binders for the shuttles boxes, a dagger, a dagger rod, a dagger spring, a dagger stop, and a part set in motion by the opening of the binders 80 due to the entrance of a shuttle into a shuttle box which is thrown by momentum against the dagger stop to cause pressure on the shuttle through the binders. 85

9. Shuttle box tension controlling mechanism for looms having, in combination, a lay, shuttle boxes for the lay, binders for the shuttle boxes, and connected mechanism acting automatically upon the entrance of a shuttle into a box to set a part of such mechanism in free motion so as to cause the momentum of such part to exert pressure of the binders on the shuttle. 90 95

In testimony whereof I have signed my name to this specification.

JONAS NORTHROP.
